[57] **CLAIM**

The ornamental design for the impact attenuating notebook computer, as shown and described.

DESCRIPTION

FIG. 1 is an isometric view of an impact attenuating notebook computer showing our new design with the screen folded down in a closed configuration in relation to the keyboard;

FIG. 2 is a top plan view of the notebook computer of FIG. 1 showing the screen folded down in a closed configuration in relation to the keyboard;

FIG. 3 is a front elevational view of the notebook computer as depicted in FIG. 2;

FIG. 4 is a side elevational view of the notebook computer as depicted in FIG. 2;

FIG. 5 is a side elevational view of the notebook computer opposite to that depicted in FIG. 4;

FIG. 6 is a rear elevational view of the notebook computer as depicted in FIG. 2;

FIG. 7 is a top plan view of the notebook computer of FIGS. 1-6 showing the screen opened in relation to the keyboard;

FIG. 8 is a front elevational view of the notebook computer as depicted in FIG. 7; and,

FIG. 9 is a bottom plan view of the notebook computer of FIGS. 1-8.
